ELECTRIC HEATING ELEMENT SUPPORT

George J. Reisch, Shelton, Conn., assignor to General Electric Company, a corporation of New York

Application June 27, 1957, Serial No. 668,363

5 Claims. (Cl. 174—138)

This invention relates to an electric heater and more particularly, to an insulator arrangement for supporting an electric heating element.

In the manufacture of electric space heaters, it has been customary to provide hook-shaped insulators which may be formed of ceramic or other suitable material for receiving and holding coiled electrical resistance heating elements. Use of these insulators presents a problem with respect to securely supporting the insulators without breaking them. An arrangement for securely holding insulators so that they do not rattle or break even though the plate upon which they may be mounted is subject to a wide range of expansion and contraction due to heating and cooling of the heater is especially desirable.

Accordingly, it is a primary object of this invention to provide an improved insulator support arrangement for securely holding insulators so that they do not rattle or break.

It is another object of this invention to provide a heating element support which is simple in structure and which may be easily installed in a supporting plate.

In accordance with one aspect of this invention, a hook-shaped insulator is provided for holding a heating element. The insulator includes a base portion having sides and a bottom surface. A recess having a side surface is formed in one side of the base portion and a step is formed on the opposite side of the base portion for co-operating with an opening formed in a supporting plate. A unique spring arrangement engages the bottom surface of the insulator base portion for urging the step and the side surface of the recess into contact with the bottom surface of the supporting plate. By this arrangement, a very simple yet effective means for easily installing insulators and for holding insulators so that they do not rattle is achieved.

Other objects and attendant advantages of this invention will be apparent from the following description taken in connection with the accompanying drawing in which:

Fig. 1 is a fragmentary plan view of the improved insulator supporting plate showing some of the insulators supported thereon;

Fig. 2 is a side elevational view of the improved insulator supporting arrangement shown in Fig. 1;

Fig. 3 is a cross sectional view of the supporting plate showing the improved insulator partially inserted in an opening formed in the supporting plate;

Fig. 4 is a cross sectional view of the supporting plate showing the insulator fully seated in the supporting plate;

Fig. 5 is a fragmentary cross sectional view of the improved spring arrangement for securely holding the insulated supports.

As illustrated in the drawings, my improved electric heating element support comprises a hook-shaped insulator 1 which is designed for connection with a supporting plate 2.

As best seen in Figs. 3 and 4, the insulator comprises an upper hook-shaped portion 3 for receiving a coiled

2

electric heating element (not shown) in a conventional manner, and a uniquely designed base portion 4 for co-operating with a generally rectangular hole 5 which is formed in supporting plate 2. As shown in Fig. 3, the length of base portion 4 from a side 6 to a side 6a thereof, is substantially larger than the length of opening 5 which is formed in base plate 2.

In order to enable base portion 4 of the insulator to be passed through opening 5, an enlarged recess 7 is provided in the right side 6 of the base portion. Recess 7 is generally V-shaped and has a bottom surface 8 and a side surface 9. With this arrangement, as shown in Fig. 3, when the bottom surface 8 of the recess is in contact with an edge of opening 5, it can be seen that the distance from bottom surface 8 to the farthest point at side 6a of the base portion 4 is less than the length of opening 5. Thus, the insulator may be positioned as shown in Fig. 3 and then rotated counterclockwise and downwardly to enable base portion 4 to be easily passed through opening 5. As shown in Fig. 4, the left side 6a of base portion 4 is provided with a step 10 which is arranged for co-operation with side 9 of recess 7 to provide seat portions on the insulator which rest against a bottom surface 11 of supporting plate 2.

A uniquely designed spring arrangement is provided for securely holding seat portions 9 and 10 in contact with the bottom surface 11 of supporting plate 2. As best seen in the right side of Fig. 2, this arrangement comprises a generally straight spring wire 12 which engages a bottom surface 13 of the base portion of the insulator. A plurality of downwardly extending apertured ears 14 may be provided on the bottom of supporting plate 2 for properly locating spring member 12. Referring now to Fig. 5, it can be appreciated that these ears 14 may easily be provided by cutting and forming sheet metal plate 2. With this arrangement, straight spring 12, may be readily threaded through the openings 15 formed by these downwardly bent ears 14. In order to restrict longitudinal movement of spring 12, one end of the spring may be bent upwardly at 16 and inserted in a hole 17 formed in supporting plate 2.

A notch 18 may be formed in the base surface 13 of base portion 4 for receiving spring 12, for restricting transverse movement of insulator holder 1 with respect to supporting plate 2, and to prevent accidental removal of insulator 1. As shown in Fig. 3, the lower surface 13 of base portion 4 at the left side of notch 18 may be gracefully curved at 19 so that spring 12 may be easily inserted into the notch without breaking the ceramic insulator 1. As shown in Fig. 4, when spring 12 is positioned in notch 18 movement of the insulator in a direction transverse to spring 12 is restricted.

Means are provided for further restricting transverse movement of insulator 1 with respect to supporting plate 2 after the insulators have been seated on side 9 of recess 5 and step 10. To achieve this, as shown in Fig. 4, an abutment 20 is formed on side surface 9 of recess 7. It can be seen that this abutment extends from the bottom surface 8 of recess 5 to an intermediate point along the side surface 9 of recess 5 and that the distance from the inside of step 10 to the outside surface of abutment 20 is only slightly less than the length of rectangular opening 5. Thus, movement of insulators 1 is effectively and conveniently restricted in a direction transverse to spring 12.

One of the most important advantages of the simplified electric heating element insulators 1 is that they are so constructed and arranged with respect to the supporting plate that they may be easily and quickly installed on the supporting plate or removed from the supporting plate.

In order to fix a ceramic insulator to supporting plate 2, it is merely necessary to pass the bottom right side of

base portion 4 of the insulator through opening 5 so that the bottom 8 of recess 7 is in contact with an edge of the opening as viewed in Fig. 3. Then the insulator may be easily snapped into position by pushing downwardly on the left side of the insulator so that straight wire 12 slips on gracefully curved portion 19 of the insulator and into notch 18. In addition, with this movement, step 10 is lowered beyond the bottom surface of supporting plate 2. A slight leftward movement will remove the right bottom edge of opening 5 from the top of abutment 20 to the side thereof so that it rests on side 9, and will cause the left edge of opening 5 to contact step 10. It can be seen readily that in forcing insulator 1 downwardly through hole 5 against spring 12, spring 12 is flexed between apertured ears 14 as shown in Fig. 2 and urges the insulator 1 upwardly towards supporting plate 2. This action firmly seats step 10 and side surface 9 of recess 5 against the bottom surface of plate 2. With this arrangement, even though supporting plate 2 expands and contracts a considerable amount due to heating and subsequent cooling of the heater, insulator elements 1 will always be firmly held in contact with plate 2 by spring 12 so that they cannot rattle against plate 2.

While there has been shown and described a particular embodiment of this invention, it will be obvious to those skilled in the art that various changes and modifications can be made therein without departing from the invention, and therefore, it is aimed by the appended claims to cover all such changes and modifications as fall within the true spirit and scope of the invention.

What I claim as new desire to secure by Letters Patent of the United States is:

1. An electric heating element support comprising: a generally hook-shaped insulator for holding a heating element, said insulator including a base portion having sides and a bottom surface, a recess having a side surface formed in one side of said base portion and a step formed on the opposite side of said base portion, a supporting plate having top and bottom surfaces; an opening formed in said plate for receiving the base portion of said insulator; and spring wire means engaging the bottom surface of said base portion for urging the step and the side surface of the recess into contact with the bottom surface of said plate.

2. An electric heating element support comprising: a generally hook-shaped insulator for holding a heating element; said insulator including a base portion having a bottom surface; a supporting plate having an opening formed therein; a recess having a side surface formed in the base portion of said insulator; a step formed in said base portion opposite to said recess; apertured ears formed on the bottom of said plate on opposite sides of said opening; and a spring wire threaded through said ears extending across said opening and engaging the bottom surface of said base portion for urging the step and the side surface of the recess into contact with the bottom of said plate.

3. An electric heating element support comprising: a generally hook-shaped insulator for holding a heating element; said insulator including a base portion having a bottom surface; a supporting plate having an opening formed therein; a recess having a side surface formed in the base portion of said insulator; a step formed in said base portion opposite to said recess; apertured ears formed on the bottom of said plate on opposite sides of said opening; a spring wire threaded through said ears extending across said opening and engaging the bottom surface of said base portion for urging the step and the side surface of the recess into contact with the bottom of said plate; and a notch formed in the bottom surface of said insulator base portion for receiving said spring wire.

4. An electric heating element support comprising: a generally hook-shaped insulator for holding a heating element, said insulator having a base portion; a supporting plate having top and bottom surfaces, an opening having edges formed in said supporting plate; a recess having a bottom and a side surface formed in the base portion of said insulator, the distance from the bottom of said recess to the farthest point on the base portion of the insulator being less than the length of said opening to enable the base portion of the insulator to be passed through said opening; a step formed in said base portion opposite to said recess; an abutment having an outside surface formed on the side surface of said recess for engaging an edge of said opening when the insulator is seated therein, the distance from the inside of the step to the outside surface of the abutment being only slightly less than the length of said opening so as to restrict transverse movement of said insulator, and a spring wire engaging said base portion for urging the step and the side surface of said recess into contact with the bottom surface of said plate.

5. An electric heating element support comprising: a fragile hook-shaped insulator for holding a heating element, said insulator including a base portion having sides and a bottom surface, a recess having a side surface formed in one side of said base portion and a step formed on the opposite side of said base portion, a sheet metal supporting plate having top and bottom surfaces; an opening formed in said plate for receiving the base portion of said insulator; and spring wire means engaging the bottom surface of said base portion for urging the step and the side surface of the recess into contact with the bottom surface of said plate.
